PREPARATION OF N-ALKYL DIETHANOL-
AMINESWilliam F. Gresham, Wilmington, Del., assignor
to E. I. du Pont de Nemours & Company, Wil-
mington, Del., a corporation of DelawareNo Drawing. Application July 8, 1944,
Serial No. 544,137

4 Claims. (Cl. 260—584)

1

This invention relates to the alkylation of organic compounds and more particularly the invention relates to the N-alkylation of dialkanolamines and to the resulting alkylated products.

An object of the present invention is to provide a process for the alkylation of dialkanolamines by the reaction of such amines with an alkyl sulfate. A further object is to provide suitable reaction conditions for conducting these alkylation reactions. Yet another object is to provide a process in which N-alkylation of dialkanolamine is effected with the formation of substantially no O-alkylated products. Other objects and advantages of the invention will hereinafter appear.

The process may be generically illustrated by this equation:

in which R and R₁ are hydrocarbon groups.

The process is conducted in accord with the invention by introducing a dialkanolamine, an alkali metal or an alkaline earth metal carbonate and an alkyl sulfate into a reaction vessel and conducting the reaction therein at a temperature between 20 and 150° C. for a period of time in the order of from 1 to 4 hours. The alkali metal and alkaline earth metal carbonates tend to decompose the alkyl sulfates. This undesirable action is minimized in accord with a preferred embodiment of the invention by the simultaneous introduction of two streams into the dialkanolamine, the dialkyl sulfate constituting one stream and an aqueous solution of the carbonate the other stream, a slight molar excess of the carbonate being used over that necessary to convert the sulfate ions liberated to sodium sulfate.

The alkanolamines that may be alkylated in accord with the invention include, more particularly, the symmetrical dialkanolamines such, for example, as diethanolamine, dipropanolamine, dibutanolamine; and the higher dialkanolamines, as well as the unsymmetrical alkyl alkanolamines, such for example as, methyl ethanolamine, ethyl ethanolamine, methyl propanolamine, etc.

The prior art does not teach how to alkylate hydroxylamine without substitution on the hydroxyl groups. In contradistinction to the processes of the art the dialkanolamines are alkylated in accord with this invention in the presence of an alkali metal carbonate and they are alkylated almost exclusively on the nitrogen group with substantially no alkylation on the oxygen of the hydroxyl groups. The alkylating agent should

2

be present preferably in amounts from 0.5 to 1.5 moles thereof per mole of the amine.

More detailed practice of the invention is illustrated by the accompanying examples of preferred embodiments of the invention in which parts are by weight unless otherwise indicated.

Example 1.—A vessel was partially filled with 52.5 parts (0.5 mole) of diethanolamine

10 into which 65 parts (0.42 mole) of diethyl sulfate was gradually added with agitation over a period of about 2 hours at a temperature of 25 to 35° C. The resulting mixture was processed for an additional period at room temperature for 8 hours. A 61% yield of N-ethyl diethanolamine ($\text{HOCH}_2\text{CH}_2\text{NC}_2\text{H}_5$) was recovered by distillation. The low yield resulted from the presence of large amounts of the O-ethyl derivatives.

20 *Example 2.*—The process of Example 1 was repeated with 105 parts (1 mole) of diethanolamine, 38.5 parts (0.25 mole) of diethyl sulfate, and 31 parts (0.25 mole) of $\text{Na}_2\text{CO}_3 \cdot \text{H}_2\text{O}$ in 30 parts (1.65 moles) of water, the diethyl sulfate and the aqueous solution of sodium carbonate being added as separate streams. The diethyl sulfate and sodium carbonate in water was gradually added with agitation in 0.5 and 1.5 hours respectively at 20 to 33° C. and 33 to 92° C. The resulting mixture was then processed for 2 hours at about 92° C. A 90.5% yield of N-ethyldiethanolamine was obtained. No O-ethylated derivatives were formed.

25 *Example 3.*—The process of Example 2 was repeated using 52.5 parts of diethanolamine, 38.5 parts of diethyl sulfate, 31 parts of $\text{Na}_2\text{CO}_3 \cdot \text{H}_2\text{O}$ in 70 parts of water. The sulfate and aqueous solution of the carbonate were added in 0.66 hours and 1.5 hours respectively at 28 to 33° C. and 33 to 92° C. The processing was continued for 2 hours at 92° C. A 91.5% yield of N-ethyl diethanolamine with no O-ethylation was obtained.

30 *Example 4.*—This example illustrates the use of a hydroxide instead of a carbonate. It will be noted that O-ethylation is not inhibited.

35 The process of Example 2 was repeated with 78.75 parts (0.75 mole) of diethanolamine, 38.5 parts (0.25 mole) of diethyl sulfate, 20 parts (0.50 mole) of sodium hydroxide and 15 parts of water. The sulfate and hydroxide were added at a temperature of 29 to 34° C. Appreciable amounts of the O-ethylation products were obtained.

40 The synthesis may, if desired, be carried out by way of a continuous process as distinguished from a batchwise process. By such a process the dialkanolamine together with the alkylating agent

with an alkali metal carbonate are introduced continuously with agitation into a reaction zone while the N-alkyl dialkanol amine is continuously withdrawn.

I claim:

1. In a process for the preparation of an N-ethyl diethanolamine substantially free from O-alkylated derivatives the step which comprises subjecting a diethanolamine to a reaction with diethyl sulfate in the presence of an aqueous solution of sodium carbonate at a temperature between 20 and 150° C. the decomposition of the alkyl sulfate being minimized by the use of a slight molar excess of the sodium carbonate over that necessary to convert the sulfate ions liberated to sodium sulfate.

2. In a process for the preparation of N-ethyl diethanolamine substantially free from O-alkylated derivatives the step which comprises subjecting 0.5 mole of diethanolamine, 0.25 mole of diethyl sulfate, 0.25 mole of $\text{Na}_2\text{CO}_3 \cdot \text{H}_2\text{O}$ and 1.65 moles of water to a reaction at a temperature of about 92° C.

3. In a process for the preparation of N-ethyl diethanolamine substantially free from O-alkylated derivatives the step which comprises gradually introducing 0.25 mole of diethyl sulfate as one stream and 0.25 mole of $\text{Na}_2\text{CO}_3 \cdot \text{H}_2\text{O}$ and 1.65

moles of water as another stream into 0.5 mole of diethanolamine and conducting the reaction at a temperature of not more than about 92° C.

4. In a process for the preparation of N-alkyl diethanolamines substantially free from O-alkylated derivatives the steps which comprise simultaneously introducing two streams of reactants into a reaction zone containing diethanolamine maintained at a temperature between 20 and 150° C., one stream consisting of a dialkyl sulfate, the other an aqueous solution of sodium carbonate, the decomposition of the alkyl sulfate being minimized by the use of a slight molar excess of the sodium carbonate over that necessary to convert the sulfate ions liberated to sodium sulfate.

WILLIAM F. GRESHAM.
